RHEOSTAT SWITCH

Hugh W. Batcheller, Newton, Mass., assignor to
 Standard Mfg. Co., Worcester, Mass., a corporation of Massachusetts

Application March 4, 1937, Serial No. 128,949

3 Claims. (Cl. 200—172)

This invention relates to improvements in rheostat switches such as are commonly employed in controlling heating units for automobiles.

5 It is an object of the present invention to provide a switch having improved structural features by which the switch can be more readily assembled and taken apart with less liability of damaging one or more of the parts in the process. It is a further object of the invention 10 to provide a switch structure having greatly improved wearing qualities.

For a more complete understanding of the invention, reference may be had to the disclosure 15 of an embodiment thereof in the description which follows and on the drawing of which

Figure 1 is an exploded perspective view of a switch mechanism embodying the invention.

Figure 2 is a longitudinal sectional view of the 20 assembled switch.

Figure 3 is a front elevation of the operating knob and shield.

Figure 4 is a perspective view of the shield.

Figure 5 is a rear elevational view of the 25 housing shell.

Figure 6 is a section on the line 6—6 of Figure 2.

Figure 7 is a front elevational view of the base member.

30 The switch structure is enclosed in a cup-shaped housing shell 10, the open end of which is normally closed by a base member 12 which fits into it. The base member is preferably of refractory material such as porcelain, molded to 35 shape, and it may be provided with a peripheral shoulder 14 against which the lip or rim of the shell bears. In order to hold the base and shell together in assembled relation, a bail 16 is provided, this bail being preferably made of resilient 40 wire bent into a U shape. The ends of the bail are hooked as at 18 to enter a pair of inclined slots 20 in opposite side walls of the shell 10. These slots slope away from the base, the remote end of each slot having a notch 22 therein.

45 The rear face of the base member 12 may be provided with a transverse groove 24 of suitable size to receive the transverse portion of the bail 16. In assembling the base member and the shell, the base 12 is inserted in the shell 10 until the edge of the shell bears against the shoulder 14. The bail 16 is then applied to the rear face 50 of the base member, the transverse portion of the bail entering the groove 24. The arms of the bail are swung around until the hooked ends 18 enter the slots 20. By pressing laterally against

the arms of the bail, the hooks 18 ride along the inclined slot 20 until they snap into the notches 22. The camming effect of the inclined slots is to put the bail under tension so that the shell is held firmly against the base member. In 5 order to provide suitable resilience in the bail, end portions 26 of the transverse part of the bail are reversely bent so as to stand away from the bottom of the groove 24. This provides spring 10 portions which yield sufficiently to permit the hooks 18 to enter the notches.

The inner or forward face of the base member 12 is provided with an arcuate groove or channel 30 within which is disposed a helical coil 32 of 15 resistance wire. The diameter of the coil is less than the width of the groove 30 but greater than its depth, so that the coil projects slightly from the groove as indicated in Figure 2. At one end 20 the groove has a portion of extra depth. In this deeper end portion of the groove the turns of the coil 32 are entirely within the groove. The groove is provided with a series of lateral recesses 34. These recesses may be on either or both sides 25 of the groove. Prior to inserting the coil 32 into the groove, a suitable amount of cementitious material is placed in the groove. Then the coil 30 is pressed into the cement so that the cement surrounds the portion of the coil which is actually within the groove and also fills the lateral recesses substantially flush with the face of the base member 12. These lateral recesses ensure 35 the presence of a sufficient amount of cement to make a good bond for the coil 32, the coil being firmly embedded in the body of cement within the groove. The portion of the coil in the deeper end portion of the groove is entirely covered by cement, and the lead wire at this end of the coil 40 is electrically connected to a metal plate 36 which is secured to the forward face of the base member as indicated in Figures 1 and 7.

Within the arc of the groove 30 and concentric therewith is a central depression 40 in the base member 12. A metal strip 42 extends radially from the depression 40 on the forward face of the base 12 and is integral with an eye 44 which projects into the recess 40. The element 42 is secured to the base as at 46 by a threaded sleeve 48 which projects through the base and receives a screw 50 at its rear end to serve as a binding post. The plate 36 is likewise secured as at 52 50 by a similar binding post.

The elements of the switch which cooperate with the elements carried by the base member 13 comprise a contact shoe 60 which may consist of a piece of sheet copper cut to suitable shape 55

and provided with an offset contact element 62 adapted to slide across the member 42 and the plate 36, and along the coil 32, and an offset contact element 64 at its other end adapted to 5 slide on the forward face of the eye 44. These contact elements 62 and 64 are preferably of substantial width so that they present as much wearing surface as possible for contact with the elements on which they slide. When the shoe 10 10 60 is in either of its extreme positions, the contact element 62 is either resting on the member 42 or is bearing on the end portion of the coil 32 remote from the plate 36. In order to rotate the shoe, it is provided with a central non-circular 15 aperture 66. In this orifice is fitted the end portion 68 of the stem 70. The stem is hollow, as indicated in Figure 2, and contains a plunger 72 which is pressed forward by a spring 74. The stem 70 passes through and fits in a non-circular 20 aperture 78 in a fiber disk 76. The disk 76 has a lug 77 projecting from its periphery to engage a tongue 79 struck up from the shell 10 to act as a stop, thus determining the extreme angular 25 positions of the shoe 60 which rotates with the disk 76. The stem 70 is permanently secured in assembled relation with the disk 76 by a pair of tongues 80 which are cut and curled out from the sides of the stem by a suitable tool after the end portion of the stem has been inserted 30 through the aperture 78. The stem 70 is preferably mounted loosely in the disk 76 so that the end portion 68, after being passed through the aperture 66 of the shoe 60, can center itself readily in the eye 44. As indicated in Figure 2, a spring 83 surrounds the end portion 68 of the stem between the disk 76 and the shoe 60. This 35 serves to press the contact elements of the shoe constantly against the respective switch elements on the base.

40 Assembled with the disk 76 are a pair of nested tubular members 84 and 86 which serve respectively as a lamp socket and shaft element. The socket 84 has a flange 88 at its rear end with notches 90 to receive a pair of ears 92 at the 45 rear end of the shaft element 86. The ears 92 pass through the notches 90 and through suitable apertures 94 in the disk 76. The ears are then bent against the rear face of the disk 76 to hold these parts permanently in assembled 50 relation. The socket 84 is provided with suitable bayonet slots 94 adapted to receive the usual pins 96 on the base 98 of a lamp bulb 100. The tip 102 of the lamp is pressed against the yielding plunger 72 when the lamp is inserted in the 55 socket.

For rotation of the disk 76 and the parts associated therewith, the shaft element 86 is keyed to another tubular shaft element 104 which telescopes thereon. The shaft 104 is notched as at 60 106 to receive a lug or key 108. This key is preferably formed by striking up from the shaft element 86 a pair of lugs on lines of bend which extend parallel to the axis of the shaft as indicated in Figures 1 and 6. These struck-up lugs 65 can be made of substantial length so as to provide a strong abutment to be engaged by the edges of the key slot 106. On the outer end of the shaft 104 is a cylindrical finger knob 110, the cylindrical surface thereof being preferably 70 knurled. This knob may be made of plastic material and is preferably molded onto the outer end of the shaft member 104 so that it becomes a permanent unit therewith. As indicated in Figure 1, the forward end of the shaft member

104 is left open so that the rays of light from the lamp 100 can shine in an axial direction. To tone down this illumination, a suitable shield 112 of translucent material may be provided, this shield being of U shape and being wide enough to cover 5 at least the open end of the shaft member 104. The arms 114 of the U-shaped shield project rearwardly and are adapted to fit frictionally on a pair of forwardly projecting arms 116 of a support member 120 which is keyed by a key 122 10 on a threaded sleeve 130, the latter being permanently attached to the shell 10 so as to form a part of the housing for the switch. As shown in Figure 3, the side portions of the finger knob 110 are exposed for access so that the knob can readily be turned.

In order to provide a yielding detent so as to indicate to the operator by the sense of touch the "on" and "off" positions of the switch and to hold the switch yieldingly in such positions, 20 the rear end 132 of the sleeve 130, which is spun against the inner face of the shell 10 so as to secure the sleeve permanently to the shell, is dented as at 134 and 136 in Figure 5. The flange 88 of the socket member 84 is pressed against the 25 rear end 132 of the sleeve 130 by the spring 82. On this flange 88 a suitable lug or bulge 140 is formed, this bulge being adapted to ride into and out of the notches 134 and 136 when the switch is in its "off" and "on" positions respectively. 30

Various modifications and changes may be made in the specific construction of the improved features of the switch herein described, without departing from the spirit or scope of the invention as defined in the following claims. 35

I claim:

1. In an electric switch, a stationary switch element, a movable switch element, and rotatable means for moving said elements into and out of contact, said means including a tubular 40 shaft having two telescoping parts, the inner part having a pair of adjacent lugs struck up from the wall thereof on lines of bend which are parallel to the axis of the shaft, the outer part having a notch therein the side edges of which 45 are engaged by said lugs.

2. In a tell-tale electric switch, a housing including a sleeve projecting therefrom, a switch within said housing, means for operating said switch, said means including a tubular shaft element having its inner end portion rotatably projecting into said sleeve and a cylindrical knob on its outer end portion, a stationary shield extending diametrically across the end of said knob and covering the end of said shaft, portions of 55 the cylindrical surface of said knob being left accessible for manipulation, and means for supporting said shield.

3. In a tell-tale electric switch, a housing including a sleeve projecting therefrom, a switch within said housing, means for operating said switch, said means including a tubular shaft element having its inner end portion rotatably projecting into said sleeve and a cylindrical knob on its outer end portion, a support element non- 60 rotatably mounted on said sleeve, said support element having a pair of parallel arms projecting forward above and below said knob, and a shield carried by said arms, said shield having a portion extending diametrically across the outer 65 end of said knob and covering the outer end of said shaft but leaving the sides of the knob exposed to access for operation of the switch.

HUGH W. BATCHELLER.
